UNITED STATES PATENT OFFICE.

JOHN H. ADAMS, OF ST. LOUIS, MISSOURI.

MACHINE FOR FOLDING PAPER.

No. 836,235.

Specification of Letters Patent.

Patented Nov. 20, 1906.

Application filed May 14, 1906. Serial No. 316,666.

To all whom it may concern:

Be it known that I, JOHN H. ADAMS, a citizen of the United States, residing at St. Louis, Missouri, have invented a new and 5 useful Machine for Folding Paper, of which the following is a specification.

This invention relates to machines for folding paper, and more particularly to machines for folding sheets of paper—such as letters, 10 circulars, and other sheets of paper—whether containing written or printed matter or not.

The object of this invention is to produce a machine of the character referred to containing mechanism operable to receive separate sheets of paper, and if such sheets be of 15 full-size letter-paper first to fold the same transversely across the center of the sheets and then to fold the sides over upon the middle portion, all the folding mechanism acting 20 automatically when in operation to produce the necessary folds. The mechanism is adjustable for folding sheets of the half or two-thirds size or other sizes, as desired, and is operable at a high rate of speed, such improvements and functions being further objects of attainment by this invention. 25

Referring to the accompanying drawings, which form part of this specification, Figure 1 is an end elevation of a machine embodying the principles of my invention. Fig. 2 is 30 a view of a sheet of paper, showing the fold-line made across a full-size letter-sheet. Fig. 3 shows the fold-lines for the sides, and Fig. 4 shows the sheet with all folds as completed 35 by the machine. Fig. 5 is a plan view of the machine. Fig. 6 is a vertical longitudinal sectional view taken approximately along the line 6 6 of Fig. 5. Fig. 7 is a detail view 40 illustrating the devices which actuate the part that produces the first transverse fold on the sheet. Fig. 8 is another view of the same devices, showing them in the act of becoming disengaged from each other.

The frames 1 carry a platform 2, having a 45 guide-plate 3 at one side to assist in arranging the paper straight prior to being started through the machine. A hinged table-wing 4 may be connected to one side of the platform 2 to hold a quantity of sheets of paper 50 in convenient position for the operator, a brace 5 serving to hold the same in horizontal position. Two rollers 7 are arranged, in this instance in the same horizontal plane, in suitable relation to a third roller 8, and a broad belt 9 passes around said rollers and 55 is kept at proper tension by some convenient

devices, such as an adjustable idle roller 10. One of the rollers 7 is power-driven; but the driving mechanism forms no part of my present invention and is not illustrated. Any of 60 the known connections for rotating said rollers may be used. A belt 11 passes around the rollers 7 at each side of the belt 9 to assist in carrying the paper straight to the folding devices. A gear-wheel 12 on one of the 65 rollers 7 meshes with a gear 13 on the shaft of an adjacent roller 14, the latter operating close to or against the belts passing around said roller 7. Between the rollers 7 a number of rollers 15 are arranged to act in coöperation 70 with the belts 9 and 11 to direct and move the paper toward the folding devices.

The paper is laid upon the platform 2 and started upon the belts 9 and 11 toward the rollers 7 14. Assuming that full-size sheets 75 of paper are being folded, the front ends of the sheets pass over the roller 14 and are kept moving in that direction until the edges strike the side of a plate 16, which is pivotally suspended from two arms 17. The arms 80 17 are connected to a plate 18, which is pivoted to two standards 19. The plate 18 extends over the roller 14 and has an edge 20 parallel with and pointing tangentially to the rollers 7 and 14 and which when lowered 85 bends and causes the paper overlying said rollers to be drawn between the rollers, thereby making a fold along the line where the said edge 20 contacted with the paper.

When the edge of a moving sheet of paper 90 strikes the pivoted plate 16, it swings said plate outward. Beyond the plate 16 a shaft 21 is journaled and is driven in this instance by a belt 22, passing around a pulley 23 on said shaft and around another pulley 24 on 95 one of the shafts 7. The adjustment is such that the shaft 21 will be rotated very rapidly. A toothed wheel 25 is attached to said shaft 21, and adjacent thereto on the plate 16 a lug or projection 26 is affixed. A cam-block 100 27 is also fastened on the plate 16, said block being comparatively thin at its upper end, but at its lower end projecting a considerable distance from the plate. The weight of the plate 16 and the parts carried thereby while 105 not great is sufficient to uphold the edge 20 of the plate 18, so that the sheets of paper may freely pass under said plate.

When the edge of the paper comes against the plate 16, the latter is swung outward and 110 the rapidly-rotating wheel 25 engages the lug or projection 26 and immediately throws

down the edge 20 of the plate 18 against the upper side of the sheet of paper, which binds the paper and causes it to be engaged and drawn between the rollers 7 and 14, forming 5 a fold, as indicated along the line 28, Fig. 2. The plate 18 being thus lowered or turned on its pivots bears close against the paper and prevents the same from buckling. The speed of rotation of the wheel 25 makes this 10 operation very rapid, and the cam-block 27 rubbing against the shaft 21 will quickly force the plate 16 away from the shaft a sufficient distance to release the lug or projection 26 from its engagement with the wheel. 15 Thereupon the plate 16 automatically lowers itself to its former position.

The paper having been thus folded transversely it is drawn beyond the rollers 7 and 14, being guided by the carrier-belt 9. A series of rollers 29 sustain the pressure on the belt between the rollers 7 and 14 and the roller 8, the upper one of said rollers 29 having a flange 30 at each side of the belt to break the fibers of the paper for the folds along the 25 lines 31, Fig. 3. A series of longitudinally-grooved rollers 32 act in connection with the rollers 29 to force the paper forward on the belt 9. A guide-plate 33 is supported below the rollers 7 and 14, the paper passing between the same and the belt 9 after it leaves 30 said rollers.

The tension of the guide-plate upon the paper may be increased or reduced by a spring-and-screw device 34, arranged in convenient position for adjustment. After the sides of the paper have been bent outward and the fibers broken by the flanges 30 the paper is carried between two flaring wings 34^a, which bend the two sides of the paper 35 over upon the middle portion, thereby completing the folds along the lines 31, formed as above described. The lower ends of the wings 34^a are very close to the belt 9, so that the sides of the paper will be folded close 40 against the middle portion. For each of the wings 34^a there is an inner wing 35, having smooth surfaces and upon which the paper is folded to prevent buckling, and the arrangement of the wings is such that one side of the 45 paper will always be folded upon the other side without interference during the passage under the wings. This is accomplished by extending one of the outer wings 34^a under the opposite inner wing 35. After passing 50 from the side folding devices the paper passes under a compression-roller 36, and thence down an inclined discharge portion of the belt to any suitable receptacle, such as 37. The folded paper is discharged endwise in the 55 receptacle 37 in such position that the discharged sections will form no obstruction to those following, so that all the sections will remain perfectly smooth and evenly folded.

When half-size sheets are to be folded, no 60 transverse folds, such as 28, are required, and

it is necessary only to fold over the sides along lines such as 31. These folds are made entirely by that mechanism beyond the rollers 7 and 14, and no fold-line is made on such half-size sheets by the edge 20 of the plate 18. 70 To accomplish this side folding, it is necessary only to direct the paper between the said rollers 7 and 14, beyond which the sides will be automatically folded over, as in the side folding of full-size sheets. For thus directing the paper the end of the plate 18 has a curved portion 38, which if the end of said plate be held down near the rollers 7 and 14 will deflect the edges of the sheets of paper between the rollers. For such purpose a 80 knob 39 is adjustably mounted on a post 40, extending through a hole in a projecting portion of the plate 18, so that by moving the knob downward on the post the curved portion 38 will be moved and held in proper position to deflect the paper between the rollers 7 and 14, as described. The belt 22 may be taken off when the machine is used for these purposes, as there is no need for rotation of the 85 shaft 21. 90

It will be obvious to those skilled in the art to which this invention pertains that the machine is capable of use by proper adjustment for folding sheets of paper of all intermediate sizes and is not restricted in its use 95 to folding the specific sizes herein referred to.

It is clear also that variations in the construction, arrangement, and operation of the parts from that herein described may be made within equivalent limits without departing from the spirit and scope of my invention. 100

Having described my invention, what I claim is—

1. In a machine for folding sheets of paper, the combination of mechanism for folding the sheets transversely, mechanism operable to fold the paper in two places after it has been folded transversely, and means to adjust the transverse folding mechanism effect- 105 ively to guide sheets of paper to said last-named mechanism without folding said sheets transversely, substantially as described.

2. In a machine of the character described, 115 the combination of a carrier-belt, two rollers operating close together, mechanism for folding a sheet of paper transversely and causing it to pass between said rollers on the carrier-belt, mechanism for folding the paper in two 120 places after it passes the said two rollers, and means to adjust the transverse folding mechanism to guide sheets of paper to said last-named mechanism without folding said sheets transversely, substantially as speci- 125 fied.

3. In a machine of the character described, 130 the combination of two rollers operating close together, devices for folding a full-size letter-sheet of paper transversely and caus-

ing it to pass between said rollers, means for adjusting said transverse folding devices to guide sheets of paper between said rollers without folding, and means to fold the paper 5 in two places after it passes said rollers, substantially as specified.

4. In a machine of the character described, the combination of a carrier-belt, two rollers operating close together, devices coöperating 10 with said rollers to fold a sheet of paper transversely and cause it to pass between said rollers on the carrier-belt, mean for adjusting said transverse folding devices to guide sheets of paper between said rollers 15 without folding, means for folding one side of a sheet over upon the middle portion after passing the rollers, and means for folding the other side of the sheet over upon the first-named side, substantially as specified.

20 5. In a paper-folding machine, the combination of two rollers, a hinged plate having a curved portion 38, means to adjust said curved portion adjacent to the rollers, means to carry paper against said curved portion 25 and between the rollers, and means for folding the two sides of the paper over upon a middle portion, substantially as specified.

6. In a paper-folding machine, the combination of folding mechanism, actuating 30 means therefor, means for causing the paper to be folded to throw said actuating means into operation, means for folding the paper after it has been folded by the first-named folding mechanism, and means for adjusting 35 the first-named folding mechanism to let the paper pass without folding, substantially as specified.

7. In a paper-folding machine, the combination of folding mechanism, actuating 40 means therefor, means for causing the paper to be folded to throw said actuating means into operation to fold the paper transversely, a carrier, a guide-plate, means for causing the paper to pass between said carrier and 45 said guide-plate after it has been folded transversely, and means for folding the sides

of the paper while passing between the carrier and guide-plate, substantially as specified.

8. In a paper-folding machine, the combination of folding mechanism, actuating 50 means therefor, means for causing the paper to be folded to throw said actuating means into operation, and means for holding the folding mechanism to guide the paper thereby without folding substantially as specified.

9. In a paper - folding machine, folding mechanism, actuating means therefor, means for causing the paper to be folded to throw the said actuating means into operation, 60 means for holding the folding mechanism to guide the paper thereby without folding it, an adjustable guide-plate, and means for folding the paper against the edges of said guide-plate, substantially as specified. 65

10. In a paper-folding machine, the combination of folding mechanism, actuating means therefor, means for causing the paper to be folded to throw said actuating means into operation, a series of folding-wings, and 70 means for causing the paper to pass between said folding-wings after it has passed the aforesaid folding mechanism, substantially as specified.

11. In a paper-folding machine, the combination with folding mechanism, and actuating means therefor, of means for causing the paper to be folded to throw said actuating means into operation, means for adjusting 80 said folding mechanism to let the paper pass without folding it, a series of flaring wings, and means for causing the paper to pass between said wings after it has passed the aforesaid folding mechanism, substantially as specified. 85

In testimony whereof I hereto affix my signature in the presence of two witnesses.
